MUSIC EDUCATIONAL TOY

William M. Jenkins, 321 E. 43rd St., New York, N.Y.

Filed June 11, 1958, Ser. No. 51,301

Term of patent 7 years

(Cl. D25—1)

The opposite side of the figure shown in FIGURE 2 is substantially the same as in FIGURE 2, the arms being reversed.

The dominant features of my design reside in the portions shown in full lines.

I claim:

The ornamental design for a music educational toy, as shown and described.
